ATTORNEYS.

Patented Oct. 27, 1925.

UNITED STATES PATENT OFFICE.

LESLIE O. WETHERELL, OF ATTLEBORO, MASSACHUSETTS, ASSIGNOR TO FREEMAN-DAUHADAY COMPANY, OF CHARTLEY, MASSACHUSETTS, A CORPORATION OF MASSACHUSETTS.

VANITY-CASE HOLDER.

Application filed July 18, 1925, Serial No. 44,457.

To all whom it may concern:

Be it known that I, LESLIE O. WETHERELL, a citizen of the United States, residing at Attleboro, in the county of Bristol and State 5 of Massachusetts, have invented certain new and useful Improvements in Vanity-Case Holders, of which the following is a specification.

This invention relates to improved means 10 for attaching a vanity case to an article of wearing apparel, and has for its object to provide such a holder member with means, whereby it may be readily connected to the apparel of the wearer, and which is adapted 15 to receive and releasably retain a vanity case or other similar receptacle.

A further object of the invention is to form this holder of a plate of sheet material having an offset clamping arm by which the 20 holder may be readily and detachably connected to the apparel of the wearer, the plate also being provided with resilient fingers between which a receptacle may be removably gripped and retained.

With these and other objects in view, the invention consists of certain novel features 25 of construction, as will be more fully described, and particularly pointed out in the appended claim.

30 In the accompanying drawing,

Figure 1 is my improved holder as attached to an article of wearing apparel and showing a vanity case as removably mounted in the holder.

35 Figure 2 is a front view illustrating the holder as struck from sheet stock with gripping fingers thereon and a holding arm formed integral therewith.

Figure 3 is a perspective view illustrating 40 the attaching arm as raised from the plane of the rear face of the plate and the resilient gripping fingers as projecting forwardly from the front face of the plate.

Figure 4 is a central sectional edge view 45 of the plate and fingers.

Figure 5 is a view partly in section showing the plate as attached to an article of wearing apparel with a receptacle mounted therein.

50 Figure 6 is a top edge view showing the plate as attached to an article of wearing apparel and showing a receptacle as held between the resilient fingers of the plate.

Figure 7 is the same as Figure 6, but

showing the ends of the fingers as shaped 55 to extend over the front edge of the receptacle to more securely retain it in position in the holder.

In the present day fashions of women's dress, there is no convenient place for 60 pockets in which to carry toilet article holders, such as vanity cases and the like, and, therefore, it has been found that the most convenient position in which to carry a small toilet-article holder such as a vanity 65 case or the like, is on a garter where it is covered by the dress and yet is in position for easy access, and, therefore, I have provided a simple and effective holder for this toilet article and have provided means 70 thereon whereby it may be readily attached to such an article of wearing apparel and have provided on the holder resilient means in which small articles such as a vanity case or the like, may be gripped and retained in 75 position where it is readily accessible, and yet be in an inconspicuous position as it is covered by the dress of the wearer; and the following is a detailed description of the present embodiment of my invention and 80 showing one means by which these advantageous results may be accomplished:—

With reference to the drawings, 10 designates the body portion or base plate of the holder, which is preferably formed of sheet 85 stock, a resilient arm member 11 being preferably cut from the body of the stock within the margin thereof to form an opening in the plate and the arm is pressed backward from the plane of the rear face of the 90 plate in position to be slid down over the upper edge of the garter 12, or other device to which it is to be attached to grip the fabric and force it into said opening to provide a more secure grip and at the same 95 time lie closely against the inner surface of the fabric, taking up the minimum amount of space.

On the periphery of this plate and extending forwardly from the front edge 100 thereof, I have formed a pair of side fingers 13 bent up to form resilient clips or fingers between which a vanity box or other receptacle 14 may be pressed and held firmly in position therein, the bottom finger 15 serving as a stop to limit the downward movement of the receptacle between the gripping fingers. It is obvious that this holder mem-

ber is not limited to be carried on the garter but may be attached to any portion of the clothing of the wearer, such as a belt, or bracelet, or even to the pocket or other portion of the clothing.

In some instances, it is found of advantage to direct the extremity or lips 16 of the finger 13 inwardly to extend over the outer edge of the receptacle so as to more firmly 10 secure the receptacle in its holder.

The foregoing description is directed solely towards the construction illustrated, but I desire it to be understood that I reserve the privilege of resorting to all the 15 mechanical changes to which the device is susceptible, the invention being defined and limited only by the terms of the appended claim.

I claim:

20 A holder for a vanity case comprising a plate of sheet material, an arm struck out

from within the margin thereof for engaging a garter or the like to press the same against the plate, diametrically opposite fingers on the edge of said plate extending outwardly at substantially right angles thereto and located at substantially the horizontal center and slightly thereabove, inturned lips on the ends of said fingers between which and said plate a circular shaped 25 vanity box may be snapped and gripped, the upper peripheral edge of said plate being free from box engaging fingers and a portion extending outwardly from the bottom of said plate to serve as a stop to limit 30 the movement of said box in being slid in a plane substantially parallel to said plate from the top thereof to a position under said lips.

In testimony whereof I affix my signature.

LESLIE O. WETHERELL.
